Primary Examiner — Barbara Fox*Assistant Examiner* — Lilyana Bekic(74) *Attorney, Agent, or Firm* — Frost Brown Todd LLC(57) **CLAIM**

The ornamental design for an oxygen mask, as shown and described.

DESCRIPTION

FIG. 1 is a front and side perspective view of an oxygen mask, showing my new design;

FIG. 2 is a front elevational view of the oxygen mask of FIG. 1;

FIG. 3 is a back elevational view of the oxygen mask of FIG. 1;

FIG. 4 is a top plan view of the oxygen mask of FIG. 1;

FIG. 5 is a bottom plan view of the oxygen mask of FIG. 1;

FIG. 6 is a left elevational view of the oxygen mask of FIG. 1;

FIG. 7 is a right elevational view of the oxygen mask of FIG. 1; and,

FIG. 8 is a cross-sectional view of the oxygen mask of FIG. 1, taken in the direction of line 8-8 of FIG. 2.

The broken lines in the drawings illustrate portions of the oxygen mask that form no part of the claimed design.
